Primary Examiner — Ruth McInroy(74) *Attorney, Agent, or Firm* — Ladas & Parry LLP(57) **CLAIM**

We claim the ornamental design for a dust canister, as shown and described.

DESCRIPTION

FIG. 1 is the front perspective view of a dust canister showing our new design;
FIG. 2 is the front view thereof;
FIG. 3 is the rear view thereof;
FIG. 4 is the left-side view thereof;
FIG. 5 is the right-side view thereof;
FIG. 6 is the top plan view thereof;
FIG. 7 is the bottom plan view thereof; and,
FIG. 8 is the bottom perspective view thereof.
The broken lines in the drawings show parts of the dust canister that form no part of the claimed design.
